United States Patent Office

Des. 188,784
Patented Sept. 13, 1960

188,784

INVALID WALKER

Donald T. Campbell, 308 E. Steward Ave., Plano, Ill.

Filed Nov. 2, 1959, Ser. No. 58,186

Term of patent 14 years

(Cl. D15—1)

Fig. 1

Fig. 2

Fig. 3

Fig. 1 is a perspective view of an invalid walker embodying my new design;

Fig. 2 is a side elevational view thereof; and

Fig. 3 is a front elevational view thereof.

I claim:

The ornamental design for an invalid walker, substantially as shown.
